RADIAL TRUCK

Cyrus J. Holland, Chicago, Cyrus E. Holland, Highland Park, and Knute Edahl, Chicago, Ill., assignors to Holland Company, a corporation of Illinois

Application April 8, 1940, Serial No. 328,468

18 Claims. (Cl. 105—167)

This invention relates to trucks for railway cars and more particularly to radial trucks.

The principal object of the invention is the provision of a new and improved high speed truck that will transport light loads with substantially the same amount of resiliency as heavy or full capacity loads and to transport the lading in such a manner as to reduce the damage or injury of the goods to a minimum.

Another object of the invention is the provision of new and improved means for causing the axles and the bolster of the truck, while the truck is on curves, to be automatically arranged radially to the curve together with novel means for automatically moving the axles back to normal position transversely to the track on passing from the curve to a straightaway track.

A further object of the invention is the provision of new and improved means for supporting a light, a heavy, or an intermediate load with approximately the same amount of resiliency and to so support the car body as to cause the same to be banked while traveling around curves.

A further object of the invention is the provision of a new and improved radial truck that is simple and rugged in construction, easily assembled, efficient in operation, and one in which the rolling, pitching, nosing or yawing of the same is reduced to a minimum.

Other and further objects and advantages of the invention will appear from the following description, taken in connection with the accompanying drawings, in which—

Fig. 1 is a plan view of a truck embodying the invention, with parts in section and parts broken away;

Fig. 2 is a diagrammatic view of a truck showing the parts in the position that they will assume in rounding a curve;

Fig. 3 is a side elevation, with parts in section;

Fig. 4 is a section on the broken line 4—4 of Fig. 1;

Fig. 5 is a side elevation of a truck showing a modified form of construction, with parts in section and parts broken away;

Fig. 6 is a section on the line 6—6 of Fig. 5;

Fig. 7 is a section on the line 7—7 of Fig. 6;

Fig. 8 is a plan view of a further modified form of construction, with parts in section and parts broken away;

Fig. 9 is a side elevation of Fig. 8, with parts broken away; and

Fig. 10 is a perspective of a modified form of roller bearings for the journal boxes.

The tendency at present in the building and

operation of railway cars is to so build the cars that they may be operated at very high speeds on curves as well as on straightaway tracks. Speeds at which cars are operated have increased tremendously in the past few years. These high speeds have brought numerous and serious problems in not only the construction but also in the riding qualities of the car bodies. With high speeds, objectionable vibrations due to inequalities in the road bed and rails are greatly multiplied. Then, too, the curves on the roads were calculated for trains traveling at much lower speeds and are not properly banked for speeds required of modern railway equipment, consequently, in the interests of safety to both the cars and the lading, suitable mechanism for automatically banking the car becomes a necessity.

On freight cars, the loads will vary from empty cars to fully loaded ones. The fully loaded ones will vary greatly in weight, depending on the lading. For instance, a load of wheat will weigh many tons more than a load of furniture and yet the same capacity springs, namely, springs that will support the maximum load, are used, with the result that the deflection for the light loads is relatively small and consequently great damage is done to the lading in partially loaded cars due to the lack of resiliency of the supporting mechanism.

It has been found that with the conventional cars carrying a static load that compresses the springs approximately $\frac{1}{4}$ " on a track having 33' rails, the critical speed for maximum harmonic vibration is about 70 miles per hour; i. e., with a speed of 70 miles per hour, harmonic vibration would be set up due to the impact of the wheels running over the joints, synchronizing with the natural period of vibration of the springs under such a load. The fully loaded car will compress the springs 1" which, on 33' rails, corresponds to a critical speed of 36 or 37 miles per hour. Since trains usually have cars that contain from no load to a full load, some cars of any freight train will, most likely, be at their critical speed when the train runs anywhere between 36 and 70 miles per hour.

With the advent of high speed trains, the friction between the rails and flanges of the wheels of the conventional rigid frame trucks on curves has greatly increased due to the centrifugal action of the car bodies. This, of course, requires additional power to transport the car. Then, too, the high speed also increases the severity of the sudden shocks caused by the contact of the wheel flange with the rail on enter-

ing the track curves. This is greatly multiplied on the rigid frame type of truck. All this is detrimental to the easy riding of the lading and results in more or less damage to the lighter and more valuable merchandise carried by the car. Numerous complaints are continuously being received by railway officials relative to damages sustained by lading of light material due to the rough riding of the car.

The present invention seeks to eliminate these difficulties by the provision of new and improved mechanism that will carry light as well as heavy loads with substantially the same amount of resiliency; that will reduce the rail shock on curves and minimize harmonic action of the spring assembly; and, that will bank the car and cause the axies to assume a radial position on curves and will automatically return the parts to normal position after passing around the curves.

Referring now to Figs. 1 to 6 of the drawings, the reference character 10 designates a railway truck of the radial type, that is, of a type in which the side frames are not connected together to form a rigid rectangular frame.

In the form of the construction selected to illustrate one embodiment of the invention, the truck is of the 4-wheeled type and comprises a pair of axles 11 and 12 having the wheels 13 rigidly mounted on the outer end portions of said axles. The truck is provided with a frame 14 at each side thereof and each frame is provided with a bolster opening 15 formed by the depending columns 16 and 17 on the sides thereof and by the top chord 18 and lower chord 19 of the side frame, as clearly shown in Fig. 3 of the drawings. The side frames are alike.

A bolster 21 extends into the openings 15 and is supported by the lower chord 19. In the form of the construction shown in Figs. 1 to 6, the bolster 21 is so mounted that on rounding curves, it will be banked; that is, the outer end will be caused to be automatically lifted while the inner end will be depressed thus banking the car supported by the bolster. Any suitable means may be provided for banking the bolster 21. As shown, rollers 22, Fig. 4, oblong in cross-section, are provided which are adapted to engage a plurality of inclined tracks or surfaces 23 and 24 on the upper and lower roller engaging or race members 25 and 26, respectively. The rollers are each provided with teeth 105 for engaging in corresponding recesses in the tracks or races for preventing skewing of rollers in use. The roller engaging or race member 25 is secured to the bolster and the roller engaging or race member 26 is secured to the lower chord 19.

The inclined tracks or surfaces 23 and 24 on the members 25 and 26, of which three are shown, are arranged to extend upwardly and outwardly so that when the car and bolster move outwardly by centrifugal action in rounding curves, the outer end of the bolster will be raised and likewise the inner end thereof will be lowered. The roller engaging or race member 26 is in direct contact with the lower chord 19 but it is understood that a spring assembly may be inserted between the roller engaging or race member 26 and the chord 19, if desired, as shown in Fig. 5.

Suitable means are provided for resiliently supporting the side frames from the axles. In the form of the construction shown in Figs. 1, 3 and 4, the axles are provided with the usual journal boxes 27 which are adapted to move vertically between the depending legs or columns 28 and

29 at each end of the side frame. The journal boxes 27, Fig. 3, are each provided with forwardly and rearwardly extending flanges 31 and 32 and on these flanges rests a saddle or an inverted U-shaped member 33 which extends over and engages the top and side portions of the journal box. The lower ends of the arms of the U are bent forwardly and rearwardly with the edges having flanges thereon to form spring seats 40 and 50. These seats are provided with downwardly extending apertured bosses 35 and 36 which engage in corresponding openings in the flanges 31 and 32 for interlocking with the saddle in its operative position. The pedestals 28 and 29, Fig. 3, which are hollow, are provided with horizontal partitions or ledges 37 and 38 which form abutments for anti-friction bearings 39 and 41.

Suitable springs or spring assemblies 42 and 43 engage spring seats 40 and 50 on the outwardly extending horizontal portions 34 of the saddle 33 and their upper ends have seated thereon, spring caps 44 and 45 carrying the lower races of the anti-friction bearings 39 and 41. These spring caps receive the upper ends of the springs, as clearly shown in Fig. 3. The springs have their lower turns 47 of greater thickness than the upper turns so that the upper turns will be more easily flexed than the lower turns. By means of this arrangement, the light loads will be supported with substantially the same resiliency as the heavier loads. In transporting the light loads, the lower turns will give sufficient flexibility to properly resiliently support the load. On heavier loads, the upper turns of the spring will engage each other so that the load will be resiliently supported by the lower turns. In this way, whether the load be heavy or light, the effective static deflection may be substantially constant.

Suitable means are provided for preventing harmonic action of the spring assembly. In the form of the construction disclosed, this is accomplished by the use of a snubber 48, Fig. 3, which, as shown, is a volute spring seated in a recess 49 formed in each of the hollow side frames above the axles. Antifriction bearings such as the roller bearings 51 may be inserted beneath the lower end of the snubber 48 and the saddle 33. The saddle 33 is provided on its upper surface with a ball or roller race and the upper race 52 is provided with corresponding curved surfaces for engaging the rollers 53. The upper surface of the race is so constructed as to constitute a seat for the lower end of the snubber 48. The roller bearings, being provided with curved seats, will assist in restoring the parts to proper position after rounding curves.

The snubber 48 may be of any suitable construction. The snubber shown is a volute spring which not only functions to prevent harmonic action of the spring assemblies 33 but is arranged in parallel with those assemblies for assisting in supporting the load, thereby increasing the capacity of the spring supporting mechanism. The volute spring cooperates with the effective constant static deflection springs 42 and 43 for supporting all types of loads at approximately a constant effective static deflection. Since the frequency of the vibration of springs is proportional to the deflection of the springs when loaded (Kent's Mechanical Engineers' Hand Book, 10th ed., p. 1555), the springs 42 and 43 may be said to have a constant frequency under variable loads. This volute spring may be similar to that

disclosed in Holland Patent 2,105,651, January 18, 1938, and need not be specifically described at this point.

Suitable means are provided for automatically adjusting the axles and the bolster radially of the curve during the travel of the track around such curve thereby relieving the lading of shocks and jars incident to the violent contact of the wheel flanges with the track on curves, as is usual in trucks having no provision for cushioning such shocks. As shown, a pair of yokes 54 and 55 are employed for this purpose. Each of these yokes extends from one side of the car to the other and is attached to the saddle 33 at each side of the car, as shown more clearly in Fig. 1 of the drawings. In the form of the construction shown, each saddle is provided with a pair of lugs 56 spaced apart and having an alined aperture therethrough. The corresponding end of the yoke 55 is provided with an eye which is positioned between the lugs 56 and a horizontal pivot bolt 57 extending through the alined openings in the lug and the yoke is provided for connecting the parts together.

The intermediate portion of each yoke is operatively connected with the central portion of the bolster. In the form of the construction shown, the bolster, on its undersurface, at its forward and rear edges, is provided with a pair of downwardly extending lugs 58 and 59 which are provided with spring seats that face each other. Each of the yokes 54 and 55 is provided with an upstanding apertured lug 61 which is positioned between the lugs 58 and 59. Springs 62 and 63 are arranged on each side of the lug 61 and engage the spring seats in the lugs 58 and 59. A bolt 64 extends axially through the springs and through alined openings in all of said lugs, as clearly shown in Fig. 4 of the drawings.

Suitable means are provided for preventing rotation of the side frames about a horizontal axis; that is, for preventing the lower portion of the side frames from spreading apart. In the form of the construction shown, the lower chords 19 are provided with inwardly extending projections 65 having upstanding bosses 66 thereon. A tie member 67 is provided with openings for engaging the bosses 66 and bolts 68, extending through the boss 66 and suitable washers 69 of a greater diameter than the boss, hold the parts in assembled relation. The openings in the ends of the tie member 67 are slightly larger than the bosses so as to provide for the slight relative movements of the side frame members in rounding a curve.

It will thus be seen that when the truck travels around curves, the centrifugal force will tend to move the car and with it the bolster 31 outwardly and this movement through the operation of the yokes will cause the outer ends of the axles to move apart and to pull their inner ends toward each other to take the positions shown in full lines in Fig. 2. In other words, the axles 11 and 12 will be moved to positions in alinement with the radii of the curve. Likewise, the bolster will be held in alinement with the radius of the curve, as shown in Fig. 2 of the drawings.

The form of the construction shown in Figs. 5 and 6 differs from the construction just described in that the bolster 121, instead of resting directly on the lower chord member 19 of the truck 10 or on the roller bearings carried thereby, has a spring assembly 71 interposed between the bolster and the lower chord 19, as shown in Fig. 5. The spring assembly 71 comprises the helical

spring 72 and a volute spring 73 which constitutes a snubber for not only assisting in supporting the load but also dampens the harmonic vibration of the spring assembly.

The yokes in this form of construction, instead of having a loose motion connection to the bolster, are each provided with an upwardly extending ball joint member 74 which engages a corresponding socket 75 carried by the forward and rear edge of the bolster, as clearly shown in Figs. 6 and 7 of the drawings. In this form of the construction, the springs 71 are similar to the springs 42 and 43 of the previous construction. These springs are of constant internal and external diameter throughout their length but the turns vary in thickness. The spring assemblies 80 for supporting the side frames from the axles are similar to the construction of the assemblies 33 in the previously described construction and function in a similar manner. In this form of construction, the roller bearings between the frames and spring assemblies are omitted, as shown in Fig. 5. These assemblies may be omitted and the side frames mounted directly on the journal boxes in the usual manner, if desired. In any event, the parts are so constructed that the axles may have a limited angular movement relative to the frames and to each other so as to permit the radial movement of the axles as described above.

The construction shown in Figs. 8 and 9 differs from that previously described in that a different arrangement for the yoke members for causing the radial movement of the axles on curves is provided. In this form of the construction, the spring supporting saddle or journal boxes are provided with forwardly and rearwardly extending lugs or arms 76 and 77, Fig. 8, for the axles 11 and 12, respectively. A U-shaped yoke member 78 is provided at opposite ends of the bolster and the arms of the yoke are attached as by means of the links 79 and 81 to the journal boxes 27, Fig. 8. The links 79 and 81 are so arranged that they converge inwardly at each side of the car. The central portion of each yoke 78 is pivotally connected to a T-shape direction member 82.

The member 82 has jaws 83 and 84, Fig. 9, on its outer end embracing the central portion of the yoke between the collars 85 and 86 and held by a bolt 87. The pivotal connection permits relative vertical movement of the bolster. The arms 88 and 89 of the T-shaped member are positioned within the ends of the bolster between the flanges 91, 93 and the flanges 92, 94, respectively, on the ends of the bolster. These flanges are angular and are turned toward each other to form spring seats facing one another. The top wall of the hollow bolster 21a is provided with a T-shaped opening 95 through which the T-shaped direction member is lowered into the bolster in assembling the parts. The flanges and arms are provided with alined openings for receiving bolts or pins 96 for holding the parts in position. Springs 97 and 98 and 99 and 100 are inserted on the bolts or pins 96 between the flanges and arms of the T-shaped member 82, respectively.

In traveling around curves, the car and bolster 21a will tend to move outward by centrifugal action and this will force the yoke 78 outward with the result that the inclined links 79 and 81 will tend to aline thus forcing the wheels on the outer side apart. Likewise, the links 79 and 81

on the inner side of the curve will tend to form a more acute angle and pull the inner wheels toward one another, thus bringing the axles 11 and 12 into alignment with the radii of the curve of the track. The bolster 21a will also remain radial to the curve. As a result of this arrangement, there will be no shocks due to violent contact of the wheel flanges with the curved rails and hence the lading will ride smoothly around curves so far as this disturbing force is concerned.

The car body, if free to move, may have, in addition to the three translations (vertical, lateral and back and forth movements), three rotations known as rolling about a longitudinal axis, pitching about a lateral transverse axis, and nosing or yawing about a vertical axis.

It will be noted that in all forms of construction of the truck, means are provided, either for resisting or for cushioning all of these movements of the car relatively to the truck. For instance, the vertical movement, the rolling, and the pitching of the car are cushioned by the spring assemblies 33 and resisted by the snubbers 48; the nosing is resisted and cushioned by the yokes and springs 62 and 63; and, the back and forth movements are resisted by the rollers 53 operating in concave races which cause the car body to tend to rise when it moves forward or back relative to the car axles. Furthermore, the conventional frictional draft gear, not shown, tends to yieldingly resist this relative forward and back movement of the car body. The swaying or lateral movement is resisted by the roller bearings 22 and by the springs 62 and 63. Furthermore, means are provided for banking the car on curves thereby tending to prevent lateral movement of the lading within the car on rounding curves. Then, too, when the train runs into a curve at high speed, impact of the flange with the curved rail before the bolster is moved by centrifugal action of the car will tend to move the axle angularly and this angular movement is resiliently resisted by the springs between the yokes and bolster and in this way the shock is, to a large extent, absorbed by these springs thus relieving the lading of the greater portion of such shocks. In other words, the parts all cooperate to prevent undue shocks being transmitted to the lading while it is being transported in cars only partially or fully loaded and under all conditions.

In Fig. 10 is shown a modified form of roller bearing for axles. These rollers are to be employed instead of the cylindrical rollers, shown in Fig. 3, for permitting swinging movement of the axles. The rollers 101 are tapered from one end to the other and, when in position on the truck, they taper inwardly so that when the axle swings, these rollers will roll in the arcs described by the journal boxes whereby the axles will move freely.

The usual safety devices have been omitted from the drawing for the sake of clearness, but it is understood they are used where necessary or desirable. For instance, means may be provided for preventing the ends of the yokes 54 and 55 from falling should the pivot bolts become lost or removed for any reason whatever. In Fig. 5 is shown an expedient for preventing the dropping of the yoke ends when the pivot pin or bolt 57 has been removed. As shown, the lugs 56 are provided with projections 102 that extend beneath the yokes 54 and 55. Each yoke may be provided with a hook-like projection 103 for en-

gaging the projection 102, which will hold the yoke from falling.

It is desirable, under certain conditions to remove the axles and wheels from the truck for replacement or repairs. If desired, the yokes may be provided with jack pads 104 under which jacks may be placed for elevating the side frames, bolster and spring assembly as a unit free from the axles and journal boxes so that the wheeled axles may be rolled out from beneath the frame.

It is thought from the foregoing, taken in connection with the accompanying drawings, that the construction and operation of our device will be apparent to those skilled in the art and that changes in size, shape, proportion and details may be made without departing from the spirit and scope of the appended claims.

We claim as our invention:

1. In a railway truck having axles and journal boxes therefor, a pair of side frame members

having bolster openings therethrough, a bolster member having its ends extending into said openings, and means for normally yieldingly biasing said bolster member normal to said side frame members, said means comprising a yoke member at each side of said bolster, each yoke having its ends pivotally connected to the journal boxes of the adjacent axle and having the junction portion of the yoke resiliently connected to said bolster.

2. In a railway truck having axles and journal boxes therefor, a pair of side frame members having bolster openings therethrough, a bolster member having its ends extending into said openings, means for yieldingly retaining said bolster member normal to said side frame members, said means comprising lugs on said bolster, a yoke member at each side of said bolster, means for connecting the ends of said yokes to adjacent journal boxes, a lug on the central portion of each yoke member between two lugs on said bolster, and springs between the lug on said yoke and each of the lugs on said bolster.

3. In a railway truck, a pair of wheeled axles spaced apart, journal boxes mounted on said axles, side frames having pedestals slidably engaging said boxes, said frames having bolster openings, a bolster extending into said openings and supported by said frames, yokes having their ends connected to said journal boxes, and means for resiliently connecting intermediate portions of said yokes to the central portion of said bolster for biasing said frames to positions normal to said bolster.

4. In a railway truck, a pair of side frames, a plurality of axles supporting said frames and movable angularly relatively to said frames, an axle box at each end of said axles, a bolster mounted on said frame, and means operated by the lateral movement of said bolster when the truck is traveling around curves to cause the wheels of said truck on the outer side of the curve to move apart and the inner wheels to approach one another, said means, including yoke members, each having its yoke ends connected to the journal boxes of one of said axles, means, including resilient elements, for yieldingly connecting the central portion of said yokes to said bolster for assisting in returning the parts to normal position after negotiating the curve.

5. In a railway truck, a pair of side frames, wheeled axles, resilient means having a substantially constant effective static deflection for all loads for supporting said frames from said axles, a bolster, means for supporting said bolster on

said frames so as to bank said bolster when the truck travels around curves, and yokes extending beneath said bolster and operatively connected to said bolster and the outer end portions of said axles for causing said axles and bolster to aline with radii of a curve during the movement of said truck around the same.

6. In a railway truck, a pair of side frames, a plurality of axles having a limited angular movement relative to said frames, means for supporting the frames from said axles, a bolster supported by said frames, means pivotally connected to said axles and having a resilient connection with said bolster for causing said axles to move angularly when said bolster moves endwise under the action of centrifugal force to aline with the radii of the curve while said truck is traveling around said curves, said resilient connection biasing said axles to normal position while the truck is traveling on a straight track.

7. In a railway truck, a side frame at each side of the truck, a plurality of axles, journal boxes for said axles, a plurality of springs for supporting said frames from said journal boxes, a laterally movable bolster supported on said frames, said springs comprising a plurality of resilient units arranged to operate in parallel, certain of said units comprising springs, their turns decreasing in cross-sectional area from one end to the other end for resiliently supporting variable loads, the remaining spring being a volute with its overlapping turns in frictional contact for preventing harmonic action of said springs, and means including yokes pivotally connected to the journal boxes and yieldingly connected to said bolster for automatically causing said axles to assume a radial position when said bolster moves laterally.

8. In a railway truck, a side frame at each side of said truck, a plurality of axles, a bolster, said axles and bolster connecting said side frames together, loose motion connections between said side frames and bolster and axles whereby the angle formed between each frame and said bolster may be greater or less than 90° while moving around a curve, resilient means for resisting angular movements of the axles relative to the side frames and for restoring the parts to normal position on a straight track, means for automatically banking said bolster when said truck is traveling around curves, and means including yokes having movable connections with said axles and resiliently connected to said bolster and operated by the inertia of the car in rounding curves for automatically moving said axles into radial position relative to said curve.

9. In a railway car having a truck provided with side frames, wheeled axles for said frames, a bolster supported by said frames, spring assemblies for supporting said frame from said axles, each assembly consisting of a plurality of helical and volute springs arranged in parallel, said volute having its turns frictionally engaging and said helicals having its turns of increasing cross-sectional area from one end to the other, yokes having movable connections with said axles, means for resiliently connecting said bolster and yokes, said bolster, yokes and connections being so constructed and arranged that the inertia of the car in rounding curves will automatically move said bolster for operating said yokes for moving said axles into radial position relative to said curve, means for banking the bolster upon rounding curves, said resilient means assisting in restoring the parts to normal position after passing from the curve to a straight-away track.

10. In a railway car having a truck provided with side frames, wheeled axles for said frames, spring assemblies for supporting said frames from said axles, each assembly consisting of a plurality of helical springs each having turns of different cross-sectional area, and at least one volute spring having its turns in frictional engagement, said frames having bolster openings therethrough, a bolster having its ends extending through said openings and provided with shoulders for loosely connecting said side frames together, means for banking said bolster upon rounding curves, and yokes having movable connections with said axles and resiliently connected to said bolster and operated by the centrifugal movement of said bolster while traveling around curves for positioning the axles in the radii of said curve.

11. In a railway truck, a plurality of axles normally parallel, side frames carried by said axles, journal boxes for said axles, a bolster, means for supporting the bolster from said frames, a yoke for each axle having its ends connected to said journal boxes, means for slidably and yieldably connecting said yokes to said bolster for cushioning the shocks due to the engagement of the wheel flange against the rails upon entering a curve in the tracks, said yokes, axles and bolster being so constructed and arranged that when said bolster moves endwise by centrifugal force as said truck rounds curves said axles will be caused thereby to move so that they will be convergent toward the inner side of the curve.

12. In a railway truck, a pair of wheeled axles spaced apart and normally parallel, journal boxes for said axles, side frames having pedestals slidably engaging said journal boxes, springs for supporting said frames from said journal boxes, a laterally movable bolster carried by said side frames, members connected to said axles and bolster and movable laterally with said bolster for causing said axles and bolster to assume positions radially of a curve while traveling around the same, and spring means interposed between said members and bolster for yieldingly resisting relative angular movement of said axles and bolster and for assisting in restoring the parts to normal position after rounding said curve.

13. In a railway truck, a pair of wheeled axles, a pair of side frames, depending pedestals on said frames at each end thereof, journal boxes on the ends of said axles between said pedestals and having a limited angular movement therein, a bolster, means for movably mounting said bolster on said frames, means connecting said axles to said bolster and so constructed that when said bolster moves outwardly by centrifugal force in rounding a curve it will cause said axles to aline with the radii of the curve, said last-named means biasing said axles to normal parallel position after rounding said curve, and means, including said first-named means, for increasingly banking said bolster on curves as the speed of the truck increases.

14. In a railway truck, a pair of side frames, a plurality of axles having wheels on the end portions thereof, means for supporting said frames from said axles with a limited relative angular movement of said axles relative to said frames, a bolster mounted on said frames, means operated by the lateral movement of said bolster under the action of centrifugal force for causing said axles to converge inwardly in traveling around curves, said means comprising a plurality of yokes, means for pivotally connecting each yoke to two journal boxes, means connecting the

yokes and bolster including yielding elements for absorbing impact shocks of the flange of the leading outer wheel against the rail in rounding curves, and means for banking said bolster on curves for assisting in cushioning the impact of said flange during the travel of the outer wheel around curves.

15. In a railway truck, a pair of side frames, wheeled axles, resilient means for supporting said frames from said axles, a bolster, means for supporting said bolster on said frame so as to bank said bolster when the truck travels around curves, yokes extending around the ends of said bolster one at each side of the truck, means for yieldingly connecting the central portions of said yokes to the ends of said bolster, respectively, and means, including links, converging inwardly for connecting the ends of each yoke to the adjacent axles.

16. A railway truck comprising a pair of axles, a pair of side frames, a bolster movably mounted on said side frames, spring means for supporting said side frames from said axles, means operated by centrifugal force for causing said axles to align with the radii of a curve while the truck is moving around the same, said means comprising a pair of yokes, means for resiliently connecting the central portion of each yoke to said bolster, means for pivotally connecting the ends of said yokes to said axles, the parts being so constructed and arranged that when said bolster moves endwise by centrifugal action on rounding curves it will react on said yokes and connections to cause said axles to be positioned radially to said curves, the resilient connection between said axles and bolster

cushioning the shocks incident to contact of the wheel flanges with the rails of the track of said curve, and a tie member connected to the lower portions of said frames for preventing their spreading apart.

17. In a railway truck, a pair of wheeled axles, journal boxes on said axles, saddles rigidly mounted on said boxes, side frames for said truck, springs for supporting said side frames from said saddles, a bolster supported by said side frames and movable laterally of the truck, yokes resiliently connected to said bolster, and means connecting the ends of each yoke to certain of the saddles for causing the saddles to move longitudinally when the yokes move laterally, thereby positioning the axles radially of a curve when the bolster moves laterally by centrifugal action on rounding said curve.

18. In a railway truck, a pair of side frames, wheeled axles, resilient means for supporting said frames from said axles, a bolster, means for supporting said bolster on said frames so as to bank said bolster when the truck travels around curves, and yokes extending beneath said bolster and having their ends operatively connected to the outer end portions of said axles, and ball and socket connections between intermediate portions of said yokes and said bolster for causing said axles and bolster to align with radii of a curve during the movement of said truck around the same.
